EDUARD WEINGÄRTNER, OF LEIPZIG-PLAGWITZ, AND WILHELM FRIESS, OF LEIPZIG-LINDENAU, GERMANY.

BRONZING OR METAL-SURFACING MACHINE.

1,140,642.

Specification of Letters Patent. Patented May 25, 1915.

Application filed April 19, 1913. Serial No. 762,368.

To all whom it may concern:

Be it known that we, EDUARD WEINGÄRTNER and WILHELM FRIESS, subjects of the Emperor of Germany, residing in Leipzig-
5 Plagwitz and Leipzig-Lindenau, Germany, respectively, have invented certain new and useful Improvements in Bronzing or Metal-Surfacing Machines, of which the following is a specification.
10 In bronzing, metal powder surfacing and like machines of the kind in which dusting or wiping devices are used consisting of bands of plush, fur felt or the like moving transversely to the sheets to be dusted and
15 in opposition to one another, such bands as a rule are moved in the plane of travel of the sheets. This is a drawback because the edges of the sheets particularly in the case of relatively thick paper sheets, being di-
20 rected against the path of travel of the dusting bands, offer a certain resistance and are worn off prematurely by the constant friction with the bands. Moreover owing to the friction the bronze dust or powder contained
25 in the bands is loosened or disturbed and thereby is caused to drop. Thus the sheets are liable to become dirty owing to the fact that not only the dropping dust but also the dust falling on the carrier laterally of the
30 sheet is caused to penetrate beneath the sheet where it adheres and in the subsequent handling of the sheets is scattered over the whole sheet pile. Further it frequently occurs that the sheet in passing through the
35 machine is seized by the bands and thereby is torn or crumpled. In order to avoid these drawbacks it has already been proposed to move the dusting bands toward the sheet from behind one of its edges and away from
40 in front of its other edge obliquely. How-
ever the carrying out of this idea has not been successful since in this operation a relatively broad strip on each of the lateral edges of the sheet is not touched by the
45 bands at all, so that the dust seated on the untouched parts of the sheet is ultimately scattered among the sheets of the pile.

Now according to this invention the draw-
50 backs above mentioned are obviated by ar-
ranging the guide rollers for the dusting bands in such a manner that the bands which travel transversely to the direction of move-
ment of the sheets are brought into contact with the latter slantingly over one edge
55 thereof, so that the bands come into contact

with the sheets inside but near one edge thereof, and then move across the sheet in contact therewith and over its opposite edge in the plane of the sheet.

Figure 1 shows in plan the arrangement 60 of the dusting bands with regard to the working table of the machine, and Fig. 2 is a front elevation of Fig. 1.

In the constructional example shown in Figs. 1 and 2 arranged at each longitudinal 65 side of the machine is a pair of rollers *a c* and *b d* respectively. Of these rollers one is adjustable in vertical direction and the other is a fixture. The rollers *a b* form one pair and the rollers *c d* the other pair of ro-
70 tatable guide rollers for the band. As shown the adjustable rollers *a d* are located in dif-
ferent planes and are arranged at a higher level than the fixed rollers *b c* as shown in Fig. 2. The endless wiping bands *e f* travel 75 each over one adjustable and one fixed roller and during the rotation of the rollers are driven in opposite directions transversely to the path of travel of the sheets across the working table of the machine. Arranged 80 between the wiping bands *e f* are two guide rollers *g h* respectively. These rollers as shown are suspended by means of bosses *i* from a stationary carrier or rod *k* on which they may be adjusted by displacement of 85 their bosses *i*. These guide rollers *g h* reach down to such a depth that the lower por-
tions of the wiping bands *e f* are held un-
der a certain amount of tension and thereby 90 are caused to exert on the sheets passing through the machine a frictional effect to such a degree that the superfluous dust or powder applied to the sheets is wiped off whereby the latter are cleaned and swept. The lower edges of the fixed rollers *b c* are 95 flush with the lower edges of the guide rollers *g h* and since the rollers *b c* are arranged outside the machine frame they have the effect that the lateral edges of the sheets are cleaned at the same time and that the superfluous powder is completely removed from the machine and further that the sheets are prevented from rising or flying up. The adjustable rollers *a d* together 100 with the guide rollers *g h* have the object to conduct the wiping bands *e f* obliquely across the lateral edges of the sheets and thus prevent the sheets from being carried along and crumpled or damaged.

Located beneath each fixed roller *b c* out- 110

side of the machine frame and in the path of the wiping bands *e f* is a rotary brush *l* or the like by which the elastic body or coating of the respective wiping band is loosened or roughened and thereby is cleaned from the dust contained therein. These roughening and cleaning brushes *l* are each arranged by preference in a casing *m*. These casings are connected to a suction apparatus where-
10 by the bronze dust or powder dropping down from the bands is conveyed to a suitable collector. It is obvious that the wiping bands can also be made to travel directly across open conduits located outside the ma-
15 chine frame and connected to the suitable suction apparatus so that in this way the dust removed from the elastic bands may be directly sucked away.

What we claim and desire to secure by
20 Letters Patent is:—

1. A dust wiping device for bronzing and like machines, comprising endless wiping bands, means for moving said bands trans-
25 versely to the path of the sheets, guide roll-
ers for said bands arranged so as to cause
the bands to be brought into contact with
the sheets slantingly over one edge thereof
so that the bands come into contact with the
30 sheets inside but near one edge thereof and
then move across the sheet in contact there-
with and over its other edge in the plane of
the sheet, substantially as set forth.

2. A dust wiping device for bronzing and like machines comprising endless wiping bands, means for moving said bands trans-
35 versely to the path of the sheets, an adjust-
able guide roller mounted at one side of
the machine, and a fixed guide roller mounted
40 at the other side of the machine for each
band, one of said guide rollers being ar-
ranged at a higher level than the other,
means for adjusting the height of said ad-
justable roller, and auxiliary guide rollers
45 arranged within said wiping bands.

3. A dust wiping device for bronzing and like machines comprising endless wiping bands, means for moving said bands trans-
50 versely to the path of the sheets, an adjust-
able guide roller mounted at one side of
the machine, and a fixed guide roller mount-

ed at the other side of the machine for each
band, one of said guide rollers being ar-
ranged at a higher level than the other,
means for adjusting the height of said ad-
justable roller, auxiliary guide rollers ar-
55 ranged within said wiping bands, and a
rotary brush located below said guide rollers
and in contact with the surface of said
bands.

4. A dust wiping device for bronzing and
like machines comprising endless wiping
bands, means for moving said bands trans-
versely to the path of the sheet, an adjust-
able guide roller mounted at one side of the
60 machine, and a fixed guide roller mounted
at the other side of the machine for each
band, one of said guide rollers being ar-
ranged at a higher level than the other,
means for adjusting the height of said ad-
65 justable roller, auxiliary guide rollers ar-
ranged within said wiping bands, and a
rotary brush located below said guide rollers
and in contact with the surface of said
bands, said brushes being arranged in a cas-
70 ing connected to a suction apparatus by
which the bronze dust or powder removed
from the bands is conveyed to a collecting
receptacle.

5. A dust wiping device for bronzing and
like machines, comprising endless wiping
bands, means for moving said bands trans-
versely to the path of the sheets, an adjust-
able guide roller mounted at one side of the
80 machine, and a fixed guide roller mounted
at the other side of the machine for each
band, one of said guide rollers being ar-
ranged at a higher level than the other,
means for adjusting the height of said ad-
85 justable roller, auxiliary guide rollers ar-
ranged within said wiping bands, and open
conduits located outside of the machine and
connected to a suction apparatus across
90 which said bands are guided.

In testimony whereof we have affixed our
signatures in presence of two witnesses.
